(57) CLAIM

The ornamental design for a counter for a bar, as shown and described.

DESCRIPTION

FIG. 1 is a top, front and side perspective view of a counter for a bar, showing my new design;

FIG. 2 is a front elevational view thereof;

FIG. 3 is an end elevational view from the left of FIG. 2;
FIG. 4 is an end elevational view from the right of FIG. 2;
and,

FIG. 5 is a top plan view thereof.

The appearance of the rear of the counter forms no part of the claimed invention.
